Primary Examiner — Kimberly Barnes(74) *Attorney, Agent, or Firm* — Oliff PLC(57) **CLAIM**

The ornamental design for a helmet core, as shown and described.

DESCRIPTION

FIG. 1 is a front, top perspective view of a helmet core, showing the new design;

FIG. 2 is a front view thereof;

FIG. 3 is a rear view thereof;

FIG. 4 is a left view thereof;

FIG. 5 is a top view thereof;

FIG. 6 is a bottom view thereof; and,

FIG. 7 is a bottom, rear perspective view thereof.

The broken lines depict parts of the helmet core that form no part of the claimed design.
